UNITED STATES PATENT OFFICE.

HENRY A. WAHLERT, OF ST. LOUIS, MISSOURI, ASSIGNOR OF ONE-HALF TO JOHN W. ADDIS,
OF MARSHALL, TEXAS.

BODY-BOLSTER.

No. 874,044.

Specification of Letters Patent.

Patented Dec. 17, 1907.

Application filed September 6, 1907. Serial No. 391,642.

To all whom it may concern:

Be it known that I, HENRY A. WAHLERT, citizen of the United States, residing at St. Louis, State of Missouri, have invented certain new and useful Improvements in Body-Bolsters, of which the following is a full, clear, and exact description, reference being had to the accompanying drawings, forming a part hereof.

10 My invention has relation to improvements in body-bolsters for railway cars; and it consists in the novel construction of bolster more fully set forth in the specification and pointed out in the claims.

15 In the drawings, Figure 1 is a top plan of my improved body-bolster, the car being shown in dotted outline; Fig. 2 is a bottom plan thereof; Fig. 3 is a side elevation of the bolster; Fig. 4 is a cross section on the line

20 4—4 of Fig. 1; Fig. 5 is a vertical section on line 5—5 of Fig. 4; Fig. 6 is an enlarged bottom plan of the forward end of the draft member showing pocket, and draw-head, and followers coupled to the draw-bar; Fig. 7 is

25 a vertical longitudinal section on the line 7—7 of Fig. 6, the coupler being in elevation; and Fig. 8 is a general diagrammatic view of the bolsters showing the truss-rod connection from end to end of a car.

30 The present invention has special application in connection with freight cars which, as well known, are subjected to maximum jars and impacts both when empty and when loaded, the object thereof being to provide a 35 body-bolster which shall have the draft members and the deadwood, usually constructed of timber, formed or cast integrally therewith, the whole forming a bolster composed of cast, or pressed steel, or malleable

40 iron, and capable not only of withstanding the impacts to which the car is subjected, but by reason of the truss-rod connection between the bolsters, resulting in a construction which distributes the impacts to the

45 best advantage so that the life of the car is materially prolonged over that of cars in which the draft timbers and dead wood are constructed of wood. The present construction too affords special provision for ar- 50 resting the movement of the followers or plates between which is located the buffer-spring of the coupler draw-bar.

The advantages of the present invention will be better apparent from a detailed de- 55 scription thereof which is as follows:

Referring to the drawings, in which parts that are old and well understood are shown in dotted outline merely, *e*, represents the end sill of the car, *s*, the side sills, and *i*, the intermediate sills, and *n*, the needle-beams, 60 these several features being old and forming no part of the present invention. Bolted to the bottom of the car, and adapted to rest on the car-truck *T*, is the body-bolster *B*, provided with side-bearings *a*, and "center-plate" *c*, the truck having suitable formations to receive these parts, well understood in the art, and requiring no extended description. Disposed at right angles to the bolster *B*, and formed integrally therewith, 65 is the draft-member *D*, taking the place of the usual wooden draft-timbers in prevailing freight car constructions. The member *D* is extended rearwardly in the form of an extension *D'* to afford a more extended bearing to the parts. The forward end of the member *D* terminates in a transverse impact or buffer member *W*, taking the place of the usual timber "dead wood" member designed 70 to receive the impact of the nose or lug *l* of 80 the draw-head of the car coupler as presently to be seen.

The upper wall of the draft-member, has formed therein a pocket or depression *p*, bounded on each side by pairs of lateral off- 85 sets or ways *d* provided with limiting walls or abutments *h*, *h'* respectively, these abutments determining the extent of movement or reciprocation of the followers or plates displaced with any sudden impact against, or 90 pull upon, the couplers or draft rigging of the car as presently to be seen.

Secured to the ends of the member *W* are the ends of the pairs of truss-rods *t*, the same passing longitudinally of the car over brackets or struts *b* on the bolster, thence under the needle-beams *n*, the rods being provided with a turn-buckle *t'* as usual (Fig. 8). While the disposition of these truss-rods is not new, yet, in the present instance, coupled 95 as they are at opposite ends to parts constituting integral formations with the body-bolster *B*, they serve to distribute to better advantage whatever strains may pass through them, since these strains are communicated 100 not only to the specific portion *B*, but to the parts *D* and *W*, as well.

As in prevailing constructions, the present bolster is equipped with the automatic coupler 1 the rear of whose draw-bar 2 is connect- 110

ed to a U-shaped strap 3 within which are loosely received the plates or followers *f*, between which the buffer-spring 4 is received. The pocket *p* previously referred to accommodates the upper arm of this strap, the parts being closed at the bottom by cover plates 6, 6' which span the space between the vertical walls or webs of the general channel cross-section in which the draft member *D* is preferably cast; and while the side walls are themselves protected by overhanging flanged formations (as shown, Figs. 2, 3) between which the securing bolts are designed to pass, it is obvious that these structural details may be varied indefinitely. The general longitudinal configuration of the part *B* is truss-shaped, the bottom walls tapering toward the ends from the center-plate *c*. Such features of construction as may be illustrated, but to which no specific reference is herein made are well understood and require no description in this connection.

The upper wall of the parts *B* and *D*, is disposed in the same plane, the terminal transverse buffer member *W* having its rear wall disposed perpendicular thereto, and extending on each side of the part *D*, the extensions being reinforced by the lateral extensions or wings *w* of said upper wall. The roof of the pocket *p* is depressed considerably below the upper edge of the member *W*, this arrangement bringing the center line of draft in line with the center line of the member *D*. Of course the end sill *e* must necessarily be notched to pass across the end of the pocket *p* but a portion of the sill will rest against the member *D* in the space *x* between the pocket and rear wall of the member *W*. The portion of the end sill resting in the space *x* will naturally serve to take up a portion of the impact to which the part *W* is subjected, the construction too, serving to tie the parts well together.

The side walls *h*, *h'* of the lateral ways *d* as before stated, serve to limit the movements of the followers *f* with any abnormal push or pull against the spring 4, one follower being pushed by the coupler draw-bar for a push and the other follower being pulled by the strap 3 for any pull between the cars. Normally, the followers would each occupy a position about midway between the walls *h*, *h'*, while the train is in motion or at a standstill.

55 The present "body bolster" therefore comprises the bolster or transverse member *B*, the draft member *D*, *D'*, and front cross-

bar or buffer member *W*, the latter projecting upward above the plane of the upper surface of the parts *B* and *D*, *D'*. The ends 60 of the buffer member merge with the surface referred to by the lateral extensions *w* already referred to. The bolsters at opposite ends of the car are united by the truss-rods *t* and the whole forms a combination 65 well tied together and difficult of displacement under the most adverse conditions.

Having described my invention what I claim is:

1. A body-bolster comprising a transverse 70 truss-shaped bolster member, a longitudinal draft member extending forward thereof, and substantially of channel cross-section, and a front cross buffer member projecting above 75 the plane of the common upper surface of the first mentioned members, the whole being formed or cast of a single piece of metal.

2. A body-bolster comprising a transverse truss-shaped bolster member, a longitudinal 80 draft member extending forward thereof and partially rearward of said bolster, and substantially of channel cross-section, a front cross buffer-member projecting above the plane of the common upper surface of the 85 first mentioned members, and lateral wings extended from said surface and meeting the base of the buffer member, the whole being formed of a single piece of metal, substantially as set forth.

3. A body-bolster comprising a bolster member of truss-shaped design disposed transversely of the car, a longitudinal channel or draft member having a rearward extension formed integrally with the bolster 95 member, an outer cross buffer member projecting above the plane of the upper surface of the bolster and draft member, lateral wings or formations forming extensions of said surface and connected to the base of the 100 buffer member, a pocket formed in the upper wall of the draft member and having lateral offsets or ways, the forward end of the pocket terminating a suitable distance from the adjacent vertical wall of the buffer member, the latter member being formed integrally with the draft member, substantially 105 as set forth.

In testimony whereof I affix my signature, in presence of two witnesses.

HENRY A. WAHLERT.
